UNITED STATES PATENT OFFICE.

FERDINAND B. PETERSON, OF NEW YORK, N. Y.

DESIGN FOR A WAFER.

52,856.

Specification for Design.

Patented Jan. 7, 1919.

Application filed October 5, 1918. Serial No. 257,067. Term of patent 14 years.

To all whom it may concern:

Be it known that I, FERDINAND B. PETERSON, a subject of the King of Sweden, residing at New York, in the county of New York and State of New York, have invented a new, original, and ornamental Design for Wafers, of which the following is a specification, reference being had to the accompanying drawing, forming part thereof.

Figure 1 is a plan view of a wafer showing my new design, and

Fig. 2 is a sectional view of a wafer showing my new design.

I claim:

The ornamental design for a wafer, as shown.

FERDINAND B. PETERSON.

Witnesses:

SOPHIE PETERSON,
JESSIE L. KNAPP.
